FREDERICK H. BRINKKOTTER, OF CALLAHAN'S RANCH, CALIFORNIA.

Letters Patent No. 94,468, dated September 7, 1869.

IMPROVEMENT IN SPOKE-TENONING MACHINE.

The Schedule referred to in these Letters Patent and making part of the same.

To all whom it may concern:

Be it known that I, FREDERICK H. BRINKKOTTER, of Callahan's Ranch, county of Siskiyou, State of California, have invented an Improved Machine for Boring Tenons on Spokes; and I do hereby declare the following description and accompanying drawings are sufficient to enable any person skilled in the art or science to which it most nearly appertains, to make and use my said invention or improvement without further invention or experiment.

My invention relates to a new and improved apparatus for turning tenons on the outer end of spokes used in wagon-wheels, so that they may be fitted into the felloe.

In constructing wagon-wheels, one of the chief difficulties is to bore the tenon on the end of the spoke perfectly true and straight, as otherwise the tenon will work in the mortise and become loose, and soon cause the wheel to give, and become worthless.

My machine consists of a frame, arranged so that the spoke to be bored is placed in position and firmly secured by clamps. The hollow auger is then set in motion, and advanced by means of a screw on the shaft by which it is propelled, until a tenon of the desired depth is turned.

In order to better illustrate my invention, reference is had to the accompanying drawings, forming a part of this specification, of which—

Figure 1 is a front view;

Figure 2 is a side view;

Figure 3 is an end view.

Similar letters of reference in each of the figures indicate like parts.

A A are the two parallel sides of the frame, and B C the two ends.

The end B is divided into two parts, the lower part being movable, and held in place by bolts passing through the upper portion B, and secured by nuts, a.

Each of these end pieces is provided with a semicircular opening, which, when the blocks are drawn together, by the bolts a', form an opening through which the spoke C' passes, and is bound by forcing the lower blocks up against the block B.

Inside of the end pieces B are cross-pieces, b, extending from side to side of the frame above and below, held together by means of bolts e.

Between the two cross-pieces are two sliding blocks, through which the bolts e pass.

These blocks are also provided with semicircular openings, through which the spoke passes, and is bound or held by the blocks being forced together by set-screws, e' e', the blocks moving in ways in the sides of the frame.

These devices secure the spoke in the desired posi-

tion for boring the tenon; and in order that it may be bored perfectly true, a bar of metal, D, bent so as to bear upon three of the spokes, and passing through slots, f f, in the sides of the frame, is employed.

This bar is placed so that its centre rests upon the spoke to be bored, its ends resting upon the spokes on each side of it and outside the frame, and is pressed down upon them by means of screws g g, thus throwing the three spokes in the same line with reference to the hub.

The wheel is secured to the frame by a ring, E, which passes down over the upper part of the hub, resting upon the spokes.

At intervals, around the inner circle of this ring, are cut inclined slots, in which small wedges, h h, are placed.

A block, F, is secured to the end of the hub by a bolt, z, which passes through it, and is secured by a nut on the upper end; and screws, i i, pass through this block and are turned down upon these wedges, thus forcing them between the hub and ring, and binding the two firmly together.

A screw, k, having a flat head, fastens into the fixed head-piece B, the head resting upon the ring E; and a pin, l, passes through a hole in the flat head of the screw, into holes n in the ring opposite each spoke, as the wheel is turned. This secures the wheel to the frame, so that each spoke will be tenoned exactly alike, as every portion is bound firmly in its proper place.

The hollow auger G, which makes the tenon, is secured at the end of a shaft, I, by a set-screw, o, so that it can be removed, if desired, for the purpose of replacing it with a different size.

The shaft passes through the end block K of the frame, and also through the slide-block L, and lies parallel to the two sides of the frame.

The end block K is arranged with two axles, p p, one at each end, which pass through vertical slots, i, in the sides of the frame A and A, and are secured in a hole in the plates s, the ends of which are formed into screws, and pass through the projecting ends of cross-pieces J, and are secured at each end by nuts s'. By loosening the screws, the end block can be raised or lowered, and the nuts tightened accordingly, for giving any desired angle or pitch to the shaft and auger.

The slide-block L moves back and forth between the sides, in slots t t, and the shaft is provided with a screw-thread where it passes through.

A clamp, which consists of the two parts u u, pivoted together at the lower part of the block L, is arranged to clasp the shaft when they are drawn together above where they are held by a staple, r, or equivalent device, which prevents them from separating.

A spring, *w*, is coiled around the shaft, between the end block *K* and slide-block *L*, which urges the slide-block forward, so as to maintain a yielding pressure upon the auger.

The wheel being first placed in position and firmly clamped, a cap, *P*, is secured to the end of the spoke, and serves to start the auger. This saves cutting down the end of the spoke, as usually necessary in starting the auger. The cap is made of steel and covered with leather or gutta-percha, to prevent it from dulling the auger. The auger is then adjusted and power applied to the shaft. The screw on the shaft, where it passes between the clamp, then feeds the auger until the desired depth of tenon is turned. The shaft is then stopped and the clamps released, after which the shaft is pushed back to place, and another spoke can be put in position for boring.

By the use of this device tenons may be quickly bored on the ends of wagon-spokes with the greatest precision, every tenon on the wheel being made on the same line with reference to the hub, which is one of the most essential points in constructing a solid and desirable wheel.

Having thus described my invention, what I claim, and desire to secure by Letters Patent, is—

1. The arrangement, between the sides *A*, of the blocks *B* and *B'*, and *d*, provided with spaces to receive the spokes, and with set-screws *e* and bolts *a*, to operate them, substantially as described.

2. In combination with the above-claimed device, the bar *D*, operated by the screws *g*, substantially as and for the purpose specified.

3. The combination and arrangement of the ring *E*, block *F*, wedges *h*, and screws *i*, substantially as and for the purpose set forth.

4. The arrangement of the block *K*, provided with axles *p*, bearing in the screw-plates *s*, and traversing in the slots *z*, substantially as and for the purpose set forth.

5. The combination and arrangement of the sliding block *L*, clamps *u*, and spring *w*, substantially as and for the purposes described.

6. The cap *P*, attached to the end of the spoke to guide the auger, substantially as described.

In witness whereof, I have hereunto set my hand and seal.

FREDERICK H. BRINKKOTTER. [L. S.]
